UNITED STATES PATENT OFFICE.

HERMAN MÜLLER, OF PHILADELPHIA, PENNSYLVANIA.

DESIGN FOR WOVEN EDGING.

41,070.

Specification for Design.

Patented Jan. 3, 1911.

Application filed July 12, 1910. Serial No. 571,666. Term of patent 7 years.

To all whom it may concern:

Be it known that I, HERMAN MÜLLER, a citizen of the United States, and a resident of Philadelphia, Pennsylvania, have invented a certain new, original, and ornamental Design for Woven Edging, of which the following is a specification, reference being had to the accompanying drawing, forming part thereof.

The figure is a face view of a piece of woven edging showing my design.

I claim:

The ornamental design for a woven edging, as shown.

HERMAN MÜLLER.
